UNITED STATES PATENT OFFICE.

GERALD W. HART, OF WEST HARTFORD, CONNECTICUT, ASSIGNOR TO THE HART & HEGEMAN MANUFACTURING COMPANY, OF HARTFORD, CONNECTICUT.

DESIGN FOR A SWITCH-HANDLE.

SPECIFICATION forming part of Design No. 26,565, dated January 26, 1897.

Application filed November 30, 1896. Serial No. 614,010. Term of patent 14 years.

To all whom it may concern:

Be it known that I, GERALD W. HART, a citizen of the United States, residing at West Hartford, county of Hartford, and State of Connecticut, have invented and produced a new and original Design for Switch-Handles, of which the following is a specification, reference being had to the accompanying drawings, forming part thereof.

Figure 1 is a perspective view of a handle embodying my design. Fig. 2 is an end elevation of the same.

The leading feature of my design consists in a vertically-fluted surface presenting in side elevation the appearance of short vertical columns and in horizontal projection the ends of such columns arranged in a straight line.

The design is shown in the drawings, in which A A' A represent three short columns which appear in the side elevation. The central one, A', is somewhat larger than the others. These columns are arranged in a straight line. At the bottom of the central column A' is a collar B. The appearance of columns is produced by vertical fluting. The fluting of the two sides is quite coarse, thus presenting to the eye, particularly in perspective, short columns in a straight line.

What I claim is—

The design for a switch-handle substantially as described and shown.

GERALD W. HART.
